US00D905633S

(12) **United States Design Patent** (10) **Patent No.:** **US D905,633 S**
Yoon (45) **Date of Patent:** **** Dec. 22, 2020**

(54) **CHARGING STAND FOR ELECTRONIC DEVICES**

(71) Applicant: **SPIGEN KOREA CO., LTD.**, Seoul (KR)

(72) Inventor: **Tae sung Yoon**, Seoul (KR)

(73) Assignee: **SPIGEN KOREA CO., LTD.**, Seoul (KR)

(**) Term: **15 Years**

(21) Appl. No.: **29/716,846**

(22) Filed: **Dec. 12, 2019**

(51) **LOC (12) Cl.** **13-02**

(52) **U.S. Cl.**

USPC **D13/108**

(57) **CLAIM**

The ornamental design for a charging stand for electronic devices, as shown and described.

DESCRIPTION

FIG. 1 is a front perspective view of a charging stand for electronic devices showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is another rear perspective view thereof.

The broken lines depict environmental subject matter and portions of the charging stand for electronic devices that form no part of the claimed design.

1 Claim, 9 Drawing Sheets
